C. F. GILCHRIST

BRUSH HOLDER

Original Filed March 4, 1920

FIG. I.

FIG. I.

FIG. III.

FIG. IV.

Inventor
Clarence F. Gilchrist

Chester H. Brantton

Attorney

UNITED STATES PATENT OFFICE.

CLARENCE F. GILCHRIST, OF TOLEDO, OHIO, ASSIGNOR TO THE ELECTRIC AUTO-LITE COMPANY, OF TOLEDO, OHIO, A CORPORATION OF OHIO.

BRUSH HOLDER.

Original application filed March 4, 1920, Serial No. 363,127. Divided and this application filed May 31, 1921. Serial No. 473,995.

To all whom it may concern:

Be it known that I, CLARENCE F. GILCHRIST, a citizen of the United States, residing at Toledo, county of Lucas, and

5 State of Ohio, have invented certain new and useful Improvements in Brush Holders, of which I declare the following to a full, clear, and exact description.

This invention relates to brush holders 10 for dynamo-electric machines and is a division of my co-pending application, Serial Number 363,127, filed March 4, 1920. It has for an object the construction of an improved brush holder and support therefor 15 which shall be simple, efficient, rugged and durable, yet adapted for economical construction and not liable to get out of order when subjected to rough treatment.

Further objects of this invention relate 20 to economies of manufacture and details of construction as will hereinafter appear from the detailed description to follow. I accomplish the objects of my invention in one instance by the devices and means described in the following specification, but 25 it is evident that the same may be varied widely without departing from the scope of the invention as pointed out in the appended claims. A structure constituting 30 one embodiment of my invention, which may be the preferred, is illustrated in the accompanying drawings forming a part hereof, in which:

Figure I is a view in partial vertical section of the commutator end of a generator 35 involving my invention.

Fig. II is a transverse sectional view taken on the line II-II of Fig. I.

Fig. III is a sectional view of a brush 40 holder and mounting plate taken on the line III-III of Fig. II.

Fig. IV is a similar view taken on the line IV-IV of Fig. II.

Referring to the drawings, a portion of a 45 generator of the enclosed type is illustrated in Figs. I and II where the casing or frame 5 has secured to it an end head 6 enclosing the commutator 7 and carrying a bearing supporting member 8. The end head 6 50 is provided with a circular central opening through which extends a flange 9 in the bearing supporting member 8, the latter serving to carry the ball bearing 10 and being mounted on the outer face of the end

head with the flange 9 projecting into the 55 interior thereof. Within the end head is a brush holder ring 12 having a pair of ears 13 at diametrically opposite points which rest against the inner face of the end head. Bolts 14 pass through slots 15 in 60 these ears and through openings in the end heads by means of which the brush holder rings are secured to the end head in proper position. A central flange 16 of the brush holder ring snugly fits over and is piloted 65 by the flange 9 of the bearing support 8.

Two similar main brushes 20 and 21 are shown carried by and rigidly secured to the brush holder ring 12 while a brush holder 22 for an auxiliary or third brush 70 is carried by the ring 12 in a manner to permit circumferential adjustment thereof.

The two brush holders 20 and 21 are similar in construction and comprise a base portion 24, a brush engaging portion 75 25, a terminal attaching portion 26, a spring supporting post 27 and a pair of securing studs or posts 28. The post 27 is shown split for the purpose of inserting the inner end of a spiral spring 30 whose outer 80 end bears against the brush 31. The studs 28 extend through openings in the ring 12 and through alining openings in two rings 32 and 33 of insulating material which lie on opposite sides of the ring 12 and which 85 are made fast thereto by rivets 34. The ends of the studs are shown upset or riveted over against washers 36 whereby the brush holder is firmly secured against the ring 12. By making the openings in the 90 ring 12 somewhat larger than the studs 28 and larger than the corresponding openings in the insulation rings 32 and 33 and by securing the rings together in fixed relation, the brush holder may be adequately 95 insulated from the ring 12 without the use of insulating sleeves for the studs.

The brush holder 22 resembles brush 100 holders 20 and 21 but is constructed to receive a somewhat narrower brush and is also provided with a securing screw 38 for holding it in adjusted position. The studs 28' of this brush holder extend through an arcuate slot 39 in the ring 12 and through corresponding slots in the two insulating rings 32 and 33 but the studs in this case serve only to position and guide the brush holder, the screw 38 serving to fix its posi- 105

tion. This brush holder is effectively insulated from the brush holding ring 12 in substantially the same manner as the previously described brush holder, as will be 5 readily apparent from an inspection of the drawing. By loosening the screw 38 the brush holder 22 may be shifted about the commutator within the limits of the slots. A split post 40 supports a spiral spring 41 10 as in the previously described brush holder.

Inasmuch as the invention herein disclosed is susceptible of various other embodiments and as various changes might be made in the embodiment set forth, it is 15 to be understood that all matter described above or shown in the accompanying drawing is to be interpreted as illustrative only, and not in a limiting sense.

Having thus described my invention, 20 what I claim as new and desire to secure by Letters Patent, is:

1. In a dynamo-electric machine, a brush holder mechanism comprising an annular plate, means for securing said plate to said 25 machine, a brush holder formed with a pair of integral projections thereon for securing said brush holder and plate together,

said plate being insulated from said holder and having openings therein to receive said projections, a post carried by said holder 30 and a brush tensioning spring carried by said post.

2. In a dynamo-electric machine, a brush holder mechanism comprising an annular plate, means for securing said plate to said 35 machine, a brush holder having a pair of integral studs formed thereon, said plate having a pair of apertures to receive said studs and said studs having their ends upset to clamp said plate.

3. In a dynamo-electric machine, a brush holder mechanism comprising an annular supporting plate having strips of insulation on opposite sides thereof, an integral brush holder including a brush engaging portion, 45 a base, and a pair of studs, said plate and strips being apertured to receive said studs and said studs being riveted over against one of said strips to securely bind said brush holder to said plate.

In testimony whereof, I affix my signature.

CLARENCE F. GILCHRIST.
